FOOD SERVING TRAY

Larry J. Jaskulek, 502 N. Daisy, and Earl A. Weber,
1181 Heatherside Road, both of Pasadena, Calif.
91107

Filed Aug. 11, 1965, Ser. No. 86,537

Term of patent 14 years

(Cl. D44—10)

FIG. 1.

FIG. 2.

FIG. 4.

FIG. 3.

FIG. 5.

FIGURE 4 is an elevational view of the food serving tray as viewed from either side of FIGURE 3; and

We claim:

The ornamental design for a food serving tray, as shown.
